US0D1089279S

(12) United States Design Patent (10) Patent No.: US D1,089,279 S
 Bieter et al. (45) Date of Patent:  Aug. 19, 2025

(54) DISPLAY SCREEN OR PORTION THEREOF WITH GRAPHICAL USER INTERFACE

(71) Applicant: Thomson Reuters Enterprises Centre GmbH, Zug (CH)

(72) Inventors: Nicholas Bieter, Saint Paul, MN (US); Brittany Shada, Farmington, MN (US); Chris Moellering, Farmington, MN (US); Jeff Arvidson, Eagan, MN (US); Doug Wozniak, Eagan, MN (US)

(73) Assignee: Thomson Reuters Enterprise Centre GmbH, Zug (CH)

() Term: 15 Years

(21) Appl. No.: 29/862,548

(22) Filed: Dec. 9, 2022

(57) CLAIM

The ornamental design for a display screen or portion thereof with graphical user interface as shown and described.

DESCRIPTION

The sole FIGURE is a front view of a display screen or portion thereof with graphical user interface showing our new design.

The outermost broken line showing of the display screen or portion thereof and the broken line showing of the remainder of the graphical user interface is for environmental purposes only and forms no part of the claimed design.

1 Claim, 1 Drawing Sheet

1. Motion to Dismiss > Denied as filed > filed by Defendant	☒ Denied as filed - June 02, 2018: The court denied as filed the Motion to Dismiss for Failure to State a Claim - Proceeding entry: 16 ☐ Order
☐ 18 Days to rule
☐ Filed - June 01, 2018: Defendants (Sheen Cowling, SC Cowling Contracting, LLC, Jaunice Watson, et. al.) filed a Motion to Dismiss for Failure to State a Claim - Proceeding entry: 16	☐ Motion
Village Builders on the Bay, Inc. v. Cowling et al 4:18-cv-00026 - May 18, 2018 Defendant's Motion to Dismiss
